FUEL SUPPLY SYSTEM AND VALVE
THEREFORClyde A. Parsons, Detroit, Mich., assignor to
McCord Radiator & Mfg. Co., Detroit, Mich.,
a corporation of MaineApplication December 31, 1931
Serial No. 584,087

9 Claims. (Cl. 158—36.4)

This invention relates to a force feed fuel supplying system for motor vehicles and a by-pass valve therefor.

The main object of the invention is to provide in a system of this character valve means whereby the pump will be able to supply fuel to the carburetor from the supply tank on the vehicle at a substantially pre-determined and constant pressure regardless of the positive or negative 10 head to which the system is subjected as the supply tank is raised or lowered by the vehicle above or below the carburetor in the travel of the vehicle over a roadway. By this arrangement, the system will not siphon through the return or by-pass 15 line to de-prime the pump when the vehicle is ascending a grade nor will the carburetor be flooded when vehicle is descending a grade. In either case, the pump will function properly to supply fuel to the carburetor at the pressure desired regardless of the position of the supply tank above or below the carburetor except for the time 20 the positive head on the system from an elevated tank becomes greater than that for which the valve is set. The system and valve means of my 25 invention are especially adaptable to motor trucks, buses and the like, where the fuel tank at the rear of the vehicle is usually at a considerable distance from the carburetor at the front of the vehicle by reason of the long length of vehicles 30 of this character. Due to the distance apart of these devices, a considerable positive or negative head is created on the system when the vehicle is descending or ascending a relatively steep grade by reason of the distance that the supply tank is 35 lowered or raised by the vehicle with respect to the carburetor. With my invention these head conditions do not affect the operation of the pump and the latter supplies fuel to the carburetor at a substantially pre-determined pressure at all 40 times.

In carrying out the objects of my invention, the valve device in the return line of the system is so constructed and designed that it may be set to determine the pressure at which the pump 45 delivers fuel to the carburetor from the supply tank. A negative head on the system by the lowering of the supply tank will not open the valve and thus the system cannot siphon back to the tank. A positive head on the valve as produced 50 by raising the tank will not open the valve except when the elevation of the tank is to such a point as to create a positive head in excess of pressure for which the valve is set. Under this condition, which is usually the extreme, the pump 55 is required to pump against whatever pressure is

developed by the positive head when it exceeds that at which the valve is set.

In the accompanying drawings:—

Fig. 1 is a diagrammatic view showing a system of the character referred to equipped with 60 a valve device of my invention;

Fig. 2 is a similar view showing the system in reversely inclined positions to be hereinafter described;

Fig. 3 is a vertical sectional view of the valve 65 device; and

Fig. 4 is an elevational view of the same.

In the drawings, 1 indicates the fuel supply tank at the rear of the vehicle. 2 indicates the carburetor at the front of the vehicle. 3 indicates 70 the intake manifold connected with the carburetor as in assemblies of this character. 4 indicates a force pump, as of the rotary type, driven from the vehicle engine, and connected with the tank and carburetor, respectively, for supplying 75 fuel to the latter from the tank at a predetermined positive pressure, as for example, four pounds. A pipe line 5 connects the tank with the pump on its intake side, while a pipe line 6 connects the carburetor with the pump on its discharge side, as shown in Figs. 1 and 2. A by-pass or return line 7 connects the pump on its discharge side with the tank through a T-fitting 8 joining pipe lines 6 and 7, as shown. A strainer 9 is in the supply line 5. A valve device 10 of my 85 invention is in the return line 7.

Valve device 10, as shown in Figs. 3 and 4, comprises a casing 11 made with its opposite ends open and closed by screw caps 12, 13. These caps clamp flexible diaphragms 14, 15 in the casing 90 on seats provided therefor at the sides of the casing. Gaskets may be employed at the edges of the diaphragms to prevent leakage past the same. The diaphragms extend across the casing in opposed relation and the space between the 95 diaphragms is divided into two chambers 16, 17, one for each diaphragm, by a partition structure arranged within the casing. This partition structure comprises horizontal webs 18, 19, one adjacent each diaphragm and a vertical web 20 extending between the horizontal webs and forming therewith seats for valve members 21, 22 carried by the respective diaphragms on the inner sides of the same. The valve members 21, 22 are secured to their respective diaphragms by fastening members 23, 24, which may be in the form of screws engaged with nuts 25, 26 on the outer sides of the diaphragms. The nuts are of such size and shape as to support coiled springs 27, 28, one for each diaphragm and lying between the 105

same and the adjacent screw cap 12, 13, as shown in Fig. 3. The springs seat in recesses in the caps, and apertures 29, 30 are provided in the caps to vent the chambers provided by the caps 5 on the outer sides of the diaphragms to the atmosphere. The caps have threaded elements 12^a, 13^a by means of which the tension of the springs 27, 28 may be adjusted to hold the valves 21, 22 closed at the same or substantially the same 10 pressure as required by my invention. The elements 12^a, 13^a are preferably in the form of screws extending into the caps through their end walls and engaging discs or plates 12^b, 13^b forming 15 movable abutments for the outer ends of the adjacent springs 27, 28. Each screw has its outer end so formed that it may be engaged for turning, and a lock nut 12^c, 13^c is provided for holding the screw in its adjusted position.

In accordance with my invention, and as shown 20 in Fig. 3, the valve device is so made that the areas of the diaphragms 14, 15 as exposed to their respective chambers 16, 17 are exactly the same, and the same is true of the valve members 21, 22. In short, the diaphragms and their respective parts are duplicates of each other, so 25 that the valve device is a balanced one regardless of which chamber 16 or 17 is connected with the discharge side of the pump and which is connected with the tank 1 through the pipe line 7. 30 To make the connections, the valve casing 11 is provided between the diaphragms with tapped holes 31, 32, the former for chamber 16 and the latter for chamber 17. In the following description of the operation of the system as equipped 35 with this valve, I will consider the chamber 16 as connected with the discharge side of the pump, and the chamber 17 as connected with the tank 1.

The pressure at which the pump 4 delivers fuel 40 to the carburetor from the tank 1 will depend on the pressure at which the springs 27, 28 are set to close their valves 21, 22. Under ordinary conditions, these springs are set to exert a four pound pressure on their valves, and the pump 4 will deliver fuel at this pressure to the carburetor 45 in the operation of the system. In case an excess pressure is created by the pump, such pressure will act through chamber 16 on diaphragm 15 and open valve 22, thus relieving the pressure through chamber 17 and return line 7. Although valve member 21 of the other diaphragm 14 is subjected to this excess pressure 50 in chamber 16, said valve will not be opened due to the larger pressure area presented by diaphragm 15.

The delivery of the pump 4 to the carburetor 55 at a predetermined pressure is in no way affected when the vehicle equipped with the herein described fuel supply system is traveling or standing on a level or substantially level roadway. At 60 this time, the parts of the system occupy the positions shown in Fig. 1. It is only when the vehicle ascends or descends a grade, and more particularly a relatively steep grade, that the discharge of the pump at a predetermined pressure 65 would be affected, if it were not for the use in the return line 7 of the valve device 10 of my invention.

When the vehicle ascends a steep grade, the 70 parts of the system occupy the positions shown in full lines in Fig. 2. Under this situation the tank 1 is lowered considerably below the carburetor and presents a condition for the pump to siphon back to the tank 1 through the return line 7. This, however, is prevented by the valve 75 device 10, due to the fact that both valves 21, 22

are held by their springs against their seats, and the portion of the return line 7 connected with the discharge side of the pump is closed to the portion connected to the tank 1. As valve 22 will not open except under an excess of pressure at 80 which the pump discharges to the carburetor, the pump will maintain that pressure regardless of the lowering of the tank 1 below the carburetor. The negative head so provided by lowering the tank will not open valve 21, and when valve 22 is opened by excess pressure created by the pump, the system will not siphon back to the tank.

When the vehicle is descending a grade, the parts of the system assume the positions shown in dot and dash lines in Fig. 2. At this time the tank 1 is raised above the carburetor and creates a positive head against diaphragm 14 through chamber 17. If this head is in excess of the closing pressure of the spring on the diaphragm, the latter will be raised and valve 21 will open admitting the pressure into chamber 16 and opening valve 22. As the pressure surfaces of both diaphragms are equal, the pressure of the positive head thereon will be equalized, and the pump will be required merely to pump against this excess pressure. Under the most extreme conditions of road grade and distance of the tank 1 from the carburetor 2, this is not excessive, and with my valve device in the return line, 100 flooding of the carburetor is prevented when the tank is elevated to create a positive head on the system in excess of that for which the valves are set.

With the valve device of my invention incorporated in the return line of the system, the pump will have its full suction qualities and capacities at all times and will be able to maintain a substantially predetermined and constant pressure on its discharge side, regardless of the 110 change in elevation of the supply tank 1 by the vehicle with respect to the carburetor as the vehicle travels over a roadway. In the drawings, the supply tank 1 is shown relatively small in diameter as compared to the pump 4 and other elements of the system. This is made necessary by reason of the small scale of the diagrammatic views of Figs. 1 and 2. In practice the tank 2 is relatively large so as to hold the required amount of fuel for the engine with 120 which the system is used.

The details of construction and arrangement of parts shown and described may be variously changed and modified without departing from the spirit and scope of my invention, except as 130 pointed out in the appended claims.

I claim as my invention:

1. In a force feed fuel supplying system for motor vehicles, a fuel supply tank and a carburetor arranged on the vehicle adjacent the 135 opposite ends of the same, a pump connected on its intake side with the tank for drawing fuel therefrom and on its discharge side with the carburetor for supply fuel thereto, a return line connecting the discharge side of the pump with the tank for by-passing fuel about the carburetor, and valve means in the return line causing the pump to deliver fuel to the carburetor at a pre-determined pressure regardless of the change in position of the tank by the vehicle 140 above or below the carburetor in the travel of the vehicle over a roadway.

2. In a force feed fuel supplying system for motor vehicles, a fuel supply tank and a carburetor arranged on the vehicle adjacent the 150

- opposite ends of the same, a pump having its intake side connected with the tank for drawing fuel therefrom and its discharge side connected with the carbureter for supplying fuel thereto, a discharge side connected with the carbureter for supplying fuel thereto, and a valve device for controlling the by-passing of fuel from the pump to the tank about the carbureter, said valve device having two chambers, one connected with the discharge side of the pump and the other connected with the tank, a pair of ports connecting said chambers, and a valve member and a flexible diaphragm therefor in each chamber for normally holding the valve member in close relation to its associated port. 80
5. In a force feed fuel supplying system for motor vehicles, a fuel supply tank and a carbureter arranged on the vehicle adjacent the opposite ends of the same, a pump having its intake side connected with the tank for drawing fuel therefrom and its discharge side connected with the carbureter for supplying fuel thereto, a return line connecting the discharge side of the pump with the supply tank for by-passing fuel about the carbureter, and valve means in the return line causing the pump to deliver fuel to the carbureter at a predetermined pressure regardless of the head produced on the valve means from the tank in the raising or lowering of the same by the vehicle above or below the carbureter in the travel of the vehicle over a roadway. 85
6. In a force feed fuel supplying system for motor vehicles, a fuel supply tank and a carbureter arranged on the vehicle adjacent the opposite ends of the same, a pump having its intake side connected with the tank for drawing fuel therefrom and its discharge side connected with the carbureter for supplying fuel thereto, a return line connecting the discharge side of the pump with the supply tank for by-passing fuel about the carbureter, and valve means in the return line causing the pump to deliver fuel to the carbureter at a pre-determined pressure whether the vehicle is on a level roadway or ascending or descending a grade. 90
7. In a force feed fuel supplying system for motor vehicles, a fuel supply tank and a carbureter, a pump having its intake side connected with the tank for drawing fuel therefrom and its discharge side connected with the carbureter for supplying fuel thereto, a return line connecting the discharge side of the pump with the tank for by-passing fuel about the carbureter, and a valve device in the return line, said valve device having normally closed valves, one controlling the pressure at which the pump delivers fuel to the carbureter, and the other controlling the opening of the valve device by the pressure condition in the return line between the valve device and the tank. 95
8. In a force feed fuel supplying system for motor vehicles, a fuel supply tank and a carbureter, a pump having its intake side connected with the tank for drawing fuel therefrom and its discharge side connected with the carbureter for supplying fuel thereto, a return line connecting the discharge side of the pump with the tank for by-passing fuel about the carbureter, and a valve device in the return line, said valve device having valves and movable pressure receiving members for normally closing the valves, one member being subject to the pressure created by the pump for controlling the pressure at which the pump delivers fuel to the carbureter, and the other member being subject to the pressure condition in the return line between the valve device and the tank, said members having substantially equal areas exposed to their respective pressures. 100
9. In a force feed fuel supplying system for motor vehicles, a fuel supply tank and a carbureter, a pump having its intake side connected with the tank for drawing fuel therefrom and its discharge side connected with the carbureter for supplying fuel thereto, and a valve device for controlling the by-passing of fuel from the pump to the tank about the carbureter, said valve device having a casing provided with two chambers, one being connected with the discharge side of the pump and the other connected with the tank, a pair of ports connecting said chambers, a valve member and a flexible diaphragm therefor in each chamber, spring means acting on the diaphragms for normally closing the valve members against their respective ports. 105
10. In a force feed fuel supplying system for motor vehicles, a fuel supply tank and a carbureter, a pump having its intake side connected with the tank for drawing fuel therefrom and its discharge side connected with the carbureter for supplying fuel thereto, a return line connecting the discharge side of the pump with the tank for by-passing fuel about the carbureter, and a valve device in the return line, said valve device having valves and movable pressure receiving members for normally closing the valves, one member being subject to the pressure created by the pump for controlling the pressure at which the pump delivers fuel to the carbureter, and the other member being subject to the pressure condition in the return line between the valve device and the tank, said members having substantially equal areas exposed to their respective pressures. 110
11. In a force feed fuel supplying system for motor vehicles, a fuel supply tank and a carbureter, a pump having its intake side connected with the tank for drawing fuel therefrom and its discharge side connected with the carbureter for supplying fuel thereto, and a valve device for controlling the by-passing of fuel from the pump to the tank about the carbureter, said valve device having two chambers, one connected with the discharge side of the pump and the other connected with the tank, a pair of ports connecting said chambers, a valve member and a flexible diaphragm therefor in each chamber, spring means acting on the diaphragms for normally closing the valve members against their respective ports, and means for adjusting the tension of the springs. 115
12. In a force feed fuel supplying system for motor vehicles, a fuel supply tank and a carbureter, a pump having its intake side connected with the tank for drawing fuel therefrom and its discharge side connected with the carbureter for supplying fuel thereto, and a valve device for controlling the by-passing of fuel from the pump to the tank about the carbureter, said valve device having two chambers, one connected with the discharge side of the pump and the other connected with the tank, a pair of ports connecting said chambers, a valve member and a movable pressure receiving element therefor in each chamber for normally closing the valve member against its associated port, the valve members and pressure elements presenting differential pressure areas to the pressures created in the respective chambers. 120
13. In a force feed fuel supplying system for motor vehicles, a fuel supply tank and a carbureter, a pump having its intake side connected with the tank for drawing fuel therefrom and its discharge side connected with the carbureter for supplying fuel thereto, and a valve device for controlling the by-passing of fuel from the pump to the tank about the carbureter, said valve device having two chambers, one connected with the discharge side of the pump and the other connected with the tank, a pair of ports connecting said chambers, a valve member and a movable pressure receiving element therefor in each chamber for normally closing the valve member against its associated port, the valve members and pressure elements presenting differential pressure areas to the pressures created in the respective chambers. 125
14. In a force feed fuel supplying system for motor vehicles, a fuel supply tank and a carbureter, a pump having its intake side connected with the tank for drawing fuel therefrom and its discharge side connected with the carbureter for supplying fuel thereto, and a valve device for controlling the by-passing of fuel from the pump to the tank about the carbureter, said valve device having two chambers, one connected with the discharge side of the pump and the other connected with the tank, a pair of ports connecting said chambers, a valve member and a movable pressure receiving element therefor in each chamber for normally closing the valve member against its associated port, the valve members and pressure elements presenting differential pressure areas to the pressures created in the respective chambers. 130
15. In a force feed fuel supplying system for motor vehicles, a fuel supply tank and a carbureter, a pump having its intake side connected with the tank for drawing fuel therefrom and its discharge side connected with the carbureter for supplying fuel thereto, and a valve device for controlling the by-passing of fuel from the pump to the tank about the carbureter, said valve device having two chambers, one connected with the discharge side of the pump and the other connected with the tank, a pair of ports connecting said chambers, a valve member and a movable pressure receiving element therefor in each chamber for normally closing the valve member against its associated port, the valve members and pressure elements presenting differential pressure areas to the pressures created in the respective chambers. 135
